UNITED STATES PATENT OFFICE.

CHARLES A. STICKNEY, OF CHICAGO, ILLINOIS.

TELEPHONE-EXCHANGE APPARATUS.

1,254,167.

Specification of Letters Patent. Patented Jan. 22, 1918.

Application filed May 15, 1916. Serial No. 97,680.

To all whom it may concern:

Be it known that I, CHARLES A. STICKNEY, a citizen of the United States, residing at Chicago, in the county of Cook and State 5 of Illinois, have invented certain new and useful Improvements in Telephone-Exchange Apparatus, of which the following is a specification.

This invention relates to improvements in 10 telephone exchange apparatus, and particularly that class of apparatus used in operating coin boxes at subscribers' stations.

One object of my invention is to provide 15 in telephone exchange apparatus means whereby a coin deposited in a coin box will be under control of the subscriber depositing the coin until the party called has answered, the control of the coin then passing from the subscriber automatically.

Another object of my invention is to provide 20 means in telephone exchange apparatus, whereby a party initiating a call by dropping a coin in the coin box may secure the return of that coin at any time prior to 25 the time the called party answers, after the operator has answered.

Another object of my invention is to provide 30 in a telephone exchange apparatus means whereby a coin deposited in a coin box by a subscriber for the purpose of calling central will be automatically returned to him should he hang up prior to the completion of the call.

Another object of my invention is to provide 35 in telephone exchange apparatus automatic means for depositing a coin, placed in a coin box by a subscriber, in the money box, the means being actuated upon the act of the answering subscriber taking his receiver from the hook.

Another object of my invention is to provide 40 a signal that will notify the operator when a coin has been deposited in the money box.

Another object of my invention is to provide 45 means in the exchange apparatus for notifying the operator when a coin has been returned to the subscriber.

With these and incidental objects in view 50 the invention consists of certain novel features of construction and combination of parts, the essential elements of which are hereinafter described with reference to the drawings which accompany and form a part 55 of this specification.

In the drawing is disclosed a schematic circuit of a subscriber's line, telephone set and coin box, and an exchange cord circuit embodying my invention.

Subscriber's telephone set "A" is connected by line wires 31 and 32 to the exchange, and also has a ground connection 33 in the coin box "B", which is closed at the contact 1 when a coin 2 is deposited and rests between the pins 3 and 4, the pin 4 being pivoted on the armature 5 at 6. Normally the contact 5 is held open by the spring 5'.

The line circuit at central station "C" has 70 a common battery 7 fed out through the relay winding 8 through the cut-off contact 9 over the line wire 31, and the relay is actuated only when a ground at 33 is provided through the closing of the contact 1 by the depositing of a coin.

The coin mechanism is shown only schematically, as the exchange apparatus is adapted to take care of different types of coin boxes, wherein the operator is signaled 75 over one side of the line to ground.

The actuation of the relay coil 8 closes the contact 10 on the line relay 8, furnishing battery for the line lamp 11.

The operator answers by inserting the 80 plug 12 into the jack 13 and battery is fed out through the repeating coil windings 14 and 15 through the winding of the supervisory relay 16 and through contacts of the switches 17 and 18 and supplies the talking set "A" with battery, and as the supervisory relay 90 16 is actuated, the battery is also fed out through the resistance 19 and 20, contact 21, wires 22, 23 and 24, through the sleeve 25 of the plug 12, sleeve 26 of the jack 13, wire 27, through the winding of the cut-off relay 95 28 to the ground, actuating the cut-off relay and opening the contact 9, thus cutting the line wires 31 and 32 from relay 8.

Having ascertained the number of the party wanted, the operator inserts her answering plug 12' into the jack corresponding to the party wanted and rings.

The sleeve 25' of the answering plug will 100 register with the sleeve of the jack in which it is inserted, and this sleeve would be connected through the cut-off relay winding associated with that line to ground in the same manner that the jack and relay cut-off winding are in the line circuit "C" and hence battery current would flow through 110

the resistance coil 19', lamp 29', through the sleeve 25', through the cut-off relay of the line of the party being called, to ground, lighting the supervisory lamp 29', and as 5 the receiver of the party being called would be upon the switch hook there would be no circuit out over line to actuate the supervisory relay 16'.

When, however, the called party answers, 10 the supervisory relay 16' would be actuated similarly as 16 in the answering side of the circuit, the contact 21' would be closed, shunting out the lamp 29' through the combined resistances in parallel of the resistance coil 20' and the switch operating coil 30'.

The operation of this coil 30' through the contact 51' would place a high voltage, preferably 110 volts, from the generator 31' 20 through the winding 32' of the coin signal relay 36', contact 33' of the switch 17, contact 34 of the switch 18, tip of the plug out over line 31 through the wire 35, the operating coils 46 of the coin box, contact 5, to the 25 frame of the coin box to the ground 33, thus actuating the mechanism and depositing the coin, the contact 5 would be opened as soon as the coin dropped through, and the circuit for the switch coil 30' would be opened by 30 the actuation of the coin signal relay 36', which is of a sluggish type to insure the depositing of the coin before the contact 51' is opened.

When the coin signaling relay 36' is actuated by current flowing through the coil 32', it is locked by battery current flowing through the lamp 41', contact 40', coil 39', wire 38', wire 37, wire 24, sleeve 25 of the plug 12, sleeve 26 of the jack 13, winding 28 35 of the cut-off relay to ground, and the relay will remain locked with the lamp 41' lighted until the operator removes the plug 12 from the jack 13, when the relay will be released and the lamp extinguished, the lamp 41' 40 serving as a signal to notify the operator when the coin has been deposited in the money box and remains as a permanent signal to that effect as long as the plug is in the jack.

50 Should the subscriber "A" for any reason wish to hang up his telephone, after the operator answers him, but prior to the called party answering, and hence before his coin has been deposited in the money box, the act 55 of hanging his receiver on the hook will open the circuit over line wires 31 and 32, and hence the relay 16 will fall back to normal, the contact 21 will be opened and the contact 42 will again be made, connecting 60 battery through the wires 43, contact 42, wire 44, switch coil 30, sleeve 25 of the plug, sleeve 26 of the jack through the winding 28 of the cut-off relay to ground, actuating the returning coin switch 18, which will send 65 110 volts from the generator 45 of the oppo-

site polarity to 31' over the line in the same manner as heretofore described, and the coin will be returned.

The 110 volt current will flow through winding 32 of the coin returning signal relay 36, lighting the lamp 41 through the locking winding 39, thus notifying the operator that the coin has been returned to the subscriber and the relay will remain locked with the signal lamp 41 illuminated until 70 the plug 12 is removed from the jack 13, thus preventing anyone from returning their own coin to themselves quickly and then allowing the operator to complete the call without knowing that the coin has passed out of control of the returning mechanism. The supervisory lamp 29 will also be illuminated when the relay 16 is deenergized by the calling subscriber hanging his receiver on his switch hook by the removal of the shunt 75 20 from around the supervisory lamp 29 and the operator will thus know when the party has hung up, remove the plugs 12 and 12' from the jacks and the apparatus will then all be in its normal condition. 80

90 While I have described my invention and illustrated in one particular design, I do not wish it understood that I limit myself to this construction, as it is evident that the application of my invention may be varied in 95 many ways within the scope of the following claims.

Claims:

1. In telephone exchange apparatus the combination of subscribers' line circuits, subscribers' telephone sets associated therewith, a coin box associated with one of said subscribers' sets, means controllable from said coin box for returning said coin, and means controllable at a called station for depositing 100 said coin, and signaling means remaining positive until the connection has been taken down at said exchange, whereby the condition of said coin is signaled to the operator at said exchange. 105

110 2. In a telephone exchange apparatus the combination of a central exchange, a plurality of line circuits having subscriber stations connected therewith at one of which is a coin box having means therein when actuated for depositing or returning a coin, means for impressing on a line circuit a super-normal voltage, means controllable from a called station for impressing said super-normal voltage in one direction on 115 said coin box line, and means at a coin box station for impressing super-normal voltage of opposite polarity on its own line.

120 3. In a telephone exchange apparatus the combination of a central exchange, a plurality of subscriber stations having subscriber sets associated therewith, a part of which have coin boxes associated with said lines, polarized means at said coin box stations 125 operable by super-normal voltage for depos- 130

iting or returning a coin placed therein, a source of super-normal voltage at said central station, means controllable at a called station for impressing said super-normal voltage of one polarity onto the calling line, and means at the calling station for impressing super-normal voltage of opposite polarity on said calling line.

4. In a telephone exchange system the combination of a central exchange, a plurality of subscriber circuits having subscriber sets associated therewith, a part of which have coin boxes associated therewith, super-

normal voltage means at said exchange whereby super-normal voltage may be applied to a line circuit in either polarity, electromagnetic means controllable from a calling coin box station for impressing super-normal voltage of one polarity on said calling line, means at said central station for rendering said controlling means inoperative when a called party has answered, and means for impressing said super-normal voltage of opposite polarity on said coin box circuit when the called party answers.

CHARLES A. STICKNEY.
